US00D963832S

(12) **United States Design Patent** (10) Patent No.: **US D963,832 S**
(45) Date of Patent: **** Sep. 13, 2022**

(54) **HANDHELD FAN WITH HOLOGRAM LED SPINNING DISPLAY**

(71) Applicant: **SHENZHEN ENO OPTOELECTRONICS TECHNOLOGY CO., LTD.**, Shenzhen (CN)

(72) Inventor: **Chunlong Yang**, Shenzhen (CN)

(73) Assignee: **SHENZHEN ENO OPTOELECTRONICS TECHNOLOGY CO., LTD.**, Shenzhen (CN)

(**) Term: **15 Years**

(21) Appl. No.: **29/806,094**

(22) Filed: **Sep. 1, 2021**

(51) LOC (13) Cl. **23-04**

(52) U.S. Cl.

USPC **D23/382**

(58) **Field of Classification Search**

(57) **CLAIM**

The ornamental design for a handheld fan with hologram LED spinning display, as shown and described.

DESCRIPTION

FIG. 1 is a perspective view of a handheld fan with hologram LED spinning display showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the handheld fan with hologram LED spinning display that form no part of the claimed design.
